UNITED STATES PATENT OFFICE.

JOHN E. PETERSON, OF NEWARK, NEW JERSEY.

TRIMMING-DIE.

1,396,230.

Specification of Letters Patent.

Patented Nov. 8, 1921.

Application filed November 8, 1920. Serial No. 422,560.

To all whom it may concern:

Be it known that I, JOHN E. PETERSON, a citizen of the United States, residing at Newark, in the county of Essex, State of New Jersey, have invented certain new and useful Improvements in Trimming-Dies, of which the following is a description, reference being had to the accompanying drawing and to the figures of reference marked thereon.

This invention relates to trimming dies and in particular to dies for trimming the edges of hollow articles.

One object of my invention is to effect the trimming of the edges of a member by means of a single downward movement of a press.

Another object is to provide a simple sturdy apparatus for this purpose comprising as few parts as is consistent with the proper operation of an apparatus of this character.

In the accompanying drawings which disclose one embodiment of my invention,—

Figure 1 is a sectional view of my trimming die showing the cup to be trimmed in place.

Fig. 2 is a view of my lower stationary die member.

Fig. 3 is a top plan view thereof.

Fig. 4 is a view of my upper movable member carrying the punch.

Fig. 5 is a bottom plan view thereof.

Figs. 6, 7 and 8 are views of the posts for guiding the movable member, showing cam surfaces thereon for shifting the punch laterally.

In the several figures in which like parts are designated by like reference characters, 1 indicates a block provided with ears 2 adapted to be secured to the bed of a press by means of suitable bolts or cap screws, not shown. The block is bored out at its center as at 3, the bore being restricted at 4 for the insertion of a shouldered tube 5. Within 45 the enlarged portion of the bore is placed the die 6 having a shearing edge 7. The die is provided with a shank 8 slidably mounted in the tube 4. A strong expansive spring 9 is coiled between the base of the shank and the lower end of the tube, said spring normally forcing the die partially out of the bore 3. To limit this movement, a stem 10 is threaded into the lower end of the shank 8 and secured in place by a set 55 pin 11. Over the lower end of the stem is passed a washer 12 and onto it is threaded

an adjusting nut 13, and a lock nut 14. It will be understood that by suitably adjusting these nuts 13 and 14 that the extent to which the die 6 will extend above the base 60 block will be limited as desired. In Fig. 2, there being no restraint on the die, the die is in its uppermost portion, with the washer 12 and nuts 13 and 14 engaging the lower end of the tube 5. The bore 3 is of a diameter to just permit the die to slide freely within the recess without permitting any wabbling of the die. The die is hollowed out to a shape corresponding to the shape of the article which is to be trimmed. In this instance it is hollowed out so as to accommodate a cup shaped member, this member being shown in cross section in Fig. 1 as seated in a substantially cylindrical recess 15 in the die 6.

In order to save machining and to permit ready insertion of the article to be operated upon, only a portion 16 of the cylinder is machined to size, the remainder being carved out so as to leave sufficient clearance for the 80 ready insertion of the article. A raised annular ring 17 is formed in the base of the cylindrical opening for the same reasons. In order to expel the article after it has been trimmed, a pin 18 is slidably mounted with 85 in a bore in the shank 8 and a spring 19 coiled in this bore and in a counterbore in the stem bears against said pin. The outward movement of the pin is limited by the enlarged head 20 thereon. Mounted in the 90 base block are any suitable number of posts of the same diameter. In this instance three have been chosen although it is to be understood that any other number may be employed depending upon the shape, size or 95 thickness of the article to be trimmed, all as will be understood after reading this specification. These parts designated as 21, 22 and 23 respectively, are each non-rotatably secured to the block by means of screws 24 100 threaded into tapped holes drilled at the juncture of the post 6 and the block, as will be readily understood. The posts are preferably arranged equally distant from one another in the circumference of a circle 105 having its center in the axis of the cylindrical recess 15 and the parts opposing the center are provided with cam surfaces as will be more particularly described farther on.

Cooperating with the lower stationary member carrying the trimming die there is

2
a movable member carrying the punch. This member comprises a block 25 adapted to be connected in any suitable manner with the movable member of the press as for example by clamping the shank 26 which is an integral part of the block to the movable member of the press. This block, like the lower stationary block is recessed at 27 and within this recess there is positioned the flange 28 of the punch 29. The flange 28 is of a diameter considerably less than the diameter of the recess 27 within the block 25, as is shown in dotted lines in Fig. 5 and is free to move around laterally in said recess. 10
15 In order to maintain the flange within the recess, a retaining ring 30 is provided, said ring being secured to the block 25 by any suitable means such as screws 31. The punch has a shearing edge 32 adapted to operate with the shearing edge 7 on the die in order to trim the article placed within the recess 15.

20 To effect the proper positioning of the cup or other article to be trimmed, a plunger 33 is slidably mounted within a bore 34 in the punch 29, said plunger being provided with a head 35 freely movable longitudinally and laterally in a counterbore 36 in the block 25. A spring 37 having an expansive force intermediate that of springs 9 and 19 urges the plunger partially out of the punch, such movement being limited by the head 35 just described.

25 The diameter of the punch is slightly less than the internal diameter of the article to be operated upon. To properly space the two shearing edges apart, a number of spacing pins 38 are provided, these pins being rigidly secured in the laterally movable flange 28 and being of such length that when they bear against the upper surface of the die 6, the shearing edge 32 will just clear the shearing edge 7 as the punch is moved laterally. From the above description, it 30
35
40
45
50
55
60
65 can be seen that as the upper member is moved downwardly, that the pins 38 will engage the die 6 and move the same downwardly against the tension of spring 9, always maintaining the die perfectly level, the shearing edge 32 meanwhile always being the same distance vertically above the shearing edge 7.

65 It is now apparent that if during this downward motion the punch be moved laterally in several different directions, that the article inserted in the die would have its edge sheared off. This is accomplished by means of inclined surfaces on the flange cooperating with the cams on the posts hereinafore referred to. The posts 21, 22 and 23 each have a rounded surface 39 adapted to fit within apertures 40 in the movable member of the trimming die, said parts acting as guide rails for the movable member. The cams on these posts 21, 22 and 23 design-

nated as 41, 42 and 43 respectively are each arranged at different levels and coöperating with these cams are three pairs of inclined surfaces 44 in the same horizontal level on the flange 28. It can now be understood that as the upper block 25 is moved downwardly onto the stationary posts that the flange 28 carrying with it the punch 29 will move successively in three different directions, moving first in a direction away from the cam 41, and then successively away from the cams 42 and 43; thus the punch and die will successfully shear off the article placed within the cylindrical recess in the die. As the movable member is raised, the flange will again move laterally in three different directions and finally the nose of the inclined portions 44 will contact with the surfaces 45 on the three posts and the flange will centralize the punch with respect to the die, these surfaces 45 all being at the same distance from the centers of the posts.

110
115
120
125
130 Rigidly secured within the recess 27 of the block 25 there is an alining pin 46 and in the flange 28 there is a hole 47 considerably larger in diameter than the pin 46 in order that lateral motion thereof with respect to the block 25 may not be restricted. The purpose of this pin and hole is to insure that the inclined surfaces on the flange 28 will be restored to the same position relative to the cams on the posts when the posts have been disassembled and are then reassembled. A line 48 is placed on one of the posts so as to permit the operator to use the same as a guide in initially setting the downward limit of movement of the block 25.

110 In operation, the block and punch are raised by the press to a height sufficient to permit the ready insertion of the untrimmed cup. Should the stroke bring the block 25 clear of the posts then on the downward stroke, the lower inclined face 44 will aline the flange 28 by abutment against the centralizing cams 45. While the block 25 is raised an untrimmed article is slipped in place. On the downward movement of the block 25 the plunger 33 will press the article in place. Further movement of the block 25 will cause the pins 38 to engage the die 6 to hold it level and press it downward. Immediately after the pins 38 have engaged the die 6 and while they are pressing down on the die 6 the flange 28 will move in its three different directions, thus effectually trimming the article. During this operation both members of the die are held perfectly level, the punch being held in a level plane by the ring 30 and the die by the pins 38 assisted by the wall of the opening 3. On the upward stroke of the block 25, the die 6 will first follow the block until stopped by the nuts 13 and 14 engaging the lower end of the tube 5. Thereafter the plunger 33 becomes noneffective and the pin 18 forces

the trimmed article to a position readily accessible for removal by the operator.

Having thus described my invention what I claim as new is:

5 1. A trimming die comprising a member having means to support an article thereon, and a member coöperating with said first named member in shearing relation therewith having motion in two different planes, 10 in order to effect said shearing relation.

2. A trimming device comprising a member movable longitudinally provided with means to support an article, a second member in shearing relationship therewith also 15 movable longitudinally and means to impart lateral movement to said second member to effect a shearing cut on the article during longitudinal movement of both members.

3. A trimming die comprising a longitudinally movable member adapted to support an article, a second member movable longitudinally therewith, means to maintain said two members at a given distance from one another during said longitudinal movement and means to impart lateral movement to said second named member during longitudinal movement of both members.

4. A trimming die comprising a base block, a member having means to support an article thereon in said base block, a member coöperating with said first named member in shearing relation therewith, means to support the second named member and means in the base block to impart a lateral 35 movement to the second named member upon movement of the supporting means.

5. A trimming die comprising a base block, a die mounted in said base block having means to support an article therein, a 40 punch coöperating with said die in shearing relationship therewith, means for supporting said punch and a unitary device secured in said base block acting as a guide for said supporting means and as a movement imparting means for said punch, said device being effective to impart movement only upon movement of the supporting means.

6. A trimming die comprising a base block, a member having means to support 50 an article thereon, said member being free to move only along its longitudinal axis and in a vertical plane within the base block, a second member in shearing relationship therewith, a support for said member, said 55 second member being free to move only in a horizontal plane with respect to said supporting member and means operative to move said second members laterally while

both members are being moved longitudinally.

7. In a trimming die, a combination of a die member, means to support an article thereon, a punch member, means to maintain said two members in a given spaced apart relationship, means tending to urge 65 said die member in one direction, the spacing means coöperating with the punch, to urge said die member in the opposite direction and means to impart both lateral and longitudinal movements to said punch member.

8. A trimming die comprising a stationary base block and a second coöperating block, a die provided with a recess slidable in said base block, a punch in said second block 75 slidable in a plane at right angles to the plane of movement of the die, a means rigidly secured in said base block to guide the second block in its movement and to impart movement to the punch as the block moves 80 and means interposed between the punch and die to insure a spacing between the two no less than a predetermined minimum value.

9. A trimming die comprising a stationary 85 base block and a second coöperating block, a die provided with a recess slidable in said base block, a pin in said die tending to expel an article adapted to be placed within said recess, a punch coöperating with said 90 die, said punch being supported by a second block, and capable of lateral movement therein, a plunger within said punch adapted to force the article adapted to be placed within the recess in place against the tendency of the pin to expel the same, means maintaining a definite spaced relationship between the punch and die, and means operative upon longitudinal movement of the second block and the die, to cause the punch 100 to move laterally in several directions.

10. A trimming die comprising a base block, a member having means to support an article therein mounted in said base block, a member coöperating with said last 105 mentioned member carrying a punch movable only in a horizontal plane, posts mounted in said block coöperating with operative portions on said horizontally movable punch to operate the same and an alined pin and 110 socket in said carrying member and said horizontally movable punch to prevent inaccurate assembling of the parts.

In testimony whereof, I affix my signature.

JOHN E. PETERSON.
